UNITED STATES PATENT OFFICE.

MYER KAMENSTEIN, OF NEW YORK, N. Y.

ASH-SIFTER.

1,228,779.

Specification of Letters Patent.

Patented June 5, 1917.

Application filed November 25, 1916. Serial No. 133,286.

To all whom it may concern:

Be it known that I, MYER KAMENSTEIN, a citizen of the United States, and a resident of New York city, in the county and State of New York, have invented certain new and useful Improvements in Ash-Sifters, of which the following is a specification.

This invention relates to an ash sifter of novel construction, and more particularly to novel and efficient means for connecting the operating shaft to the wire mesh drum.

In the accompanying drawing:

Figure 1 is a longitudinal section of an ash sifter embodying my invention;

Fig. 2, a cross section on line 2—2 Fig. 1.

Fig. 3, a perspective view of the seaming strip;

Fig. 4, a perspective view of the shaft coupling strap, and

Fig. 5, a cross section through the drum joint.

The sifter comprises essentially, a hopper 1 which communicates with one of the open heads 2 of a casing 3, the other open head 4 of which carries a hook 5, from which a pail adapted to receive the sifted coal may be suspended. Casing 3 is open at the bottom and is mounted on a flanged annular base 6, by which the device may be mounted upon a barrel adapted to receive the ashes. Through casing 3 extends an inclined shaft 7 journaled in hopper 1 and head 4 and furnished at one end with a crank handle 8. Shaft 7 extends axially through a correspondingly inclined wire mesh screening drum 9, and is connected to said drum by a pair of straps 10 and 11, which extend diametrically across the latter at right angles to each other. Of these, strap 10 is furnished with a central aperture for the accommodation of shaft 7, and has bent ends which are riveted to one of a pair of bands 12, encircling the respective ends of the drum. Strap 11 extends with its flat faces at right angles to the shaft and is provided at its center with a laterally extending integral bulge or U-shaped loop 13, the web or central member of which is apertured as at

40 44 for the reception of shaft 7, that extends longitudinally through the loop. The two 45

opposed sides of the loop are likewise apertured as at 15, for the reception of a cotter pin 16 which also passes through an aligned transverse aperture of shaft 7. The two 55 perforated ends of strap 11 are bent outwardly and are riveted to the second band 12 of drum 9.

By the construction described, the drum is coupled to the shaft in a simple manner, and 60 will be positively taken along by the latter, even under the severe strain to which drums of this class are subjected when in use.

The two longitudinal edges of drum 9, face each other and are connected by means 65 of a binder, more fully shown in Figs. 3 and 5. This binder is composed of a strip of sheet metal 17 which extends from end to end of the drum. Strip 17 is so bent as to form above its inner face, a pair of opposed doubled flanges 18, each of said flanges forming between its walls an outwardly directed narrow groove or pocket 19. The two abutting edges of the drum, are inserted into their respective grooves so 70 as to be straddled by the flanges, and then strip 17 is riveted to the bands 12 as at 20 so that in this way, the drum becomes seamed in a simple and reliable manner.

I claim:

1. A shaft bearing comprising a strap having a laterally extending integral U-shaped loop provided with a pair of parallel apertured sides and an apertured end, a shaft extending longitudinally through said loop and passing through said apertured end, a pin engaging the shaft and passing through said apertured sides, and a rotatable member carrying the strap.

2. A shaft bearing comprising a strap 90 having bent ends and a laterally extending integral U-shaped loop provided with a pair of parallel apertured sides and an apertured end, a shaft extending longitudinally through said loop and passing through said apertured end, a pin engaging the shaft and passing through said apertured sides, a rotatable member, a band carried by said member, and means for connecting the bent ends to said band.

MYER KAMENSTEIN.
